UNITED STATES PATENT OFFICE.

ANDREW A. MULLEN, OF NEW YORK, N. Y.

DESIGN FOR A SKELETON PAVING-BRICK.

No. 39,654.

Specification for Design.

Patented Oct. 27, 1908.

Application filed December 8, 1906. Serial No. 346,996. Term of patent 14 years.

To all whom it may concern:

Be it known that I, ANDREW A. MULLEN, a citizen of the United States, residing at Wakefield, New York city, in the county of New York and State of New York, have invented a new, original, and ornamental Design for Skeleton Paving-Brick, of which the following is a specification.

In the drawings—Figure 1 is a perspective view of a skeleton paving brick embodying

the herein-described design. Fig. 2 is a top plan view thereof. Fig. 3 is a side elevation.

What I claim is:—

The ornamental design for a skeleton paving brick, as shown.

ANDREW A. MULLEN.
